UNITED STATES PATENT OFFICE.

WILLARD D. SMITH, OF MAPLEWOOD, MISSOURI, AND HARRY D. SMITH, OF EAST ST. LOUIS, ILLINOIS, ASSIGNORS TO ST. LOUIS PUMP & EQUIPMENT COMPANY, OF ST. LOUIS, MISSOURI, A CORPORATION OF MISSOURI.

OIL PUMP.

Application filed November 24, 1923. Serial No. 676,821.

This invention relates to liquid-handling apparatus, and with regard to certain more specific features, to a visible hand-measuring pump for oil and the like.

5 Among the several objects of the invention may be noted the provision of a simple and compact structure permitting the customer to view the goods about to be delivered to him; the provision of an inexpensive and durable arrangement of concentric opaque and translucent cylinders, between which the liquid passes on its way to the dispensing orifice; and the provision of improved means for displaying the true color 10 of the liquid that is being dispensed. Other objects will be in part obvious and in part pointed out hereinafter.

The invention accordingly consists of the elements and combinations of elements, features of construction, and arrangement of parts which will be exemplified in the structure hereinafter described and the scope of the application of which will be indicated in the following claims.

25 In the accompanying drawings, in which is shown one of various possible embodiments of the invention,

Fig. 1 is a vertical section on the line 1—1 of Fig. 2;

30 Fig. 2 is a top plan view;

Fig. 3 is a horizontal section on the line 3—3 of Fig. 1;

Fig. 4 is a front elevation;

35 Fig. 5 is a horizontal section on the line 5—5 of Fig. 4; and

Fig. 6 is a plan view of a fibre gasket.

Similar reference characters indicate corresponding parts throughout the several views of the drawings.

40 Referring now more particularly to Figs. 1 and 2 of the accompanying drawings, there is illustrated a pump comprising a polished metal cylinder 1 preferably of brass, within which reciprocates a piston 3 fixed 45 to the rack 5 which meshes with a pinion 7 driven by a hand crank 9. The downward stroke of the piston is limited by the shoulder or abutment 11 of the frame 13. The upward stroke of the piston is adjust- 50 ably limited by the set screw 15 mounted in a cap 17 threaded upon the tube 19 that houses the rack 5. The set screw is locked in position by a lock nut 21.

The entire pump is adapted to be mount-

ed upon a threaded pipe (not shown) extending upwardly from a source of supply of liquid, such as an oil tank. The threaded pipe fits into the internally threaded projection 23 at the lower end of the pump.

55 Rotation of the hand crank 9 in a clockwise direction (Fig. 1) raises the rack and piston and causes liquid to be drawn from the source of supply (not shown) connected to the threaded projection 23, upwardly through the passage 25, past the ball check 27 into the chamber 29. As the piston rises, oil is drawn into the chamber 29 and ordinarily fills the space 31 beneath the piston. This may be termed the filling stroke of the 60 piston.

65 On the downward or dispensing stroke of the piston the liquid passes from the space 31 and chamber 29 through the second ball check 33 and thence upwardly through a plurality of holes 37 (Figs. 3 and 6) in a 70 fibre washer or gasket 39 (Fig. 6). The liquid is then forced upwardly through the annular space 41 between the brass cylinder 1 and a glass cylinder 43 mounted outside the brass cylinder and concentrically disposed with relation to the latter.

75 The brass cylinder preferably has a polished nickel surface. The liquid, coming up between the brass and glass cylinder, is visible to the customer. The metal cylinder reflects the light incident upon it, so that the liquid is given substantially its natural color. The customer is thus able to judge accurately the nature and quality of the liquid 80 that is being delivered to him. This is particularly true because the radial distance between the two cylinders is small enough (preferably about one-fourth inch) so that plenty of light passes through the liquid to the metal cylinder and is there reflected.

85 When the liquid reaches the upper end of the glass cylinder it passes again through a plurality of holes 45 (Fig. 5) in a fibre gasket 47. The gasket resembles the gasket 39 (Fig. 6) above described. The liquid 90 passes thence through the nozzle 49, having an anti-splash tube 50 in the end thereof. The nozzle may be provided with a hook 51 on which to hang a container for receiving the dispensed liquid.

100 The rack 5 is held in position with respect to the piston 3 by a lock nut 53 (Fig. 1). The piston has a peripheral slot for receiv-

ing a helical spring 55 (Fig. 1) which serves to press outwardly against the metal cylinder 1 a plunger leather 57. A nut 59 threaded on the lower portion of the piston serves to retain the plunger leather against displacement with respect to the piston.

The brass and glass cylinders 1, 43, are mounted in concentric slots in the under face of the top casting 61 and in similar slots 10 in the upper face of the bottom casting 13.

The top and bottom castings 61, 13, are held together by three tension rods 63 (Fig. 3) and are held apart by the metal and glass cylinders 1, 43.

15 The lower casting 13 is approximately cylindrical and has two projections 67, 69 extending from it at diametrically opposite points, to house the discharge valve 33 and intake valve 27 respectively.

20 The two valves each comprise a tube 71 threaded at each end and having wrench slots 73 in its lower edge. Each tube is threaded at its upper end into the lower casting 13. The upper end of each tube is the seat for 25 the valve ball. Each tube has a cap 75 threaded on its lower end.

At the end of the pinion shaft 77 opposite the handle 9 is a counter 79 (Figs. 2 and 5) driven through a ratchet (not shown), so that the counter is actuated only upon the 30 down stroke of the piston.

As soon as some liquid has been dispensed from the pump, the annular space between the metal and glass cylinders remains full 35 of liquid and thus displays to customers the quality of liquid that the pump delivers.

One of the three tension rods 63 (Fig. 1) is utilized as a passageway 81 between the lower side of the intake check valve 27 and the upper side of the piston. This prevents the formation of a vacuum in the space above 40 the piston, and carries away any liquid which may leak past the plunger leather.

In view of the above, it is believed that 45 the various features of this invention will be clear without further elaboration, and it will be seen that with the apparatus herein described, the several objects of the inven-

tion are achieved and other advantageous results attained.

As many changes could be made in carrying out the above construction without departing from the scope of the invention, it is intended that all matter contained in the above description or shown in the accompanying drawings shall be interpreted as illustrative and not in a limiting sense.

We claim:

1. In apparatus of the class described, in combination, a cylinder reflecting light incident upon its outer surface, a translucent cylinder surrounding the first cylinder, a piston within the first cylinder, means for reciprocating the piston and means adapted to cause said reciprocating piston to pump liquid through the passage between said cylinders.

2. In apparatus of the class described, in combination, a cylinder reflecting light incident upon its outer surface, a translucent cylinder surrounding the first cylinder and separated a short radial distance therefrom, a piston within the first cylinder, means for reciprocating the piston; a conduit leading from the first cylinder to a source of supply having an inwardly opening check valve 75 therein, and a passage leading from said first cylinder to the space between cylinders said passage being provided with an outwardly opening check valve.

3. An apparatus of the class described, in combination, a cylinder, a translucent cylinder surrounding the first cylinder and separated a short radial distance therefrom as compared with the cylinder diameters, a piston within the first cylinder, means for reciprocating the piston to pump liquid for dispensing and display purposes through the passage between the cylinders, whereby the liquid may be viewed thoroughly with minimized diffraction.

In testimony whereof, we have signed our names to this specification this 22d day of November, 1923.

WILLARD D. SMITH.
HARRY D. SMITH.
